*E. Morris,
Slate Frame,*

No. 11,134.

Patented June 20, 1854.

UNITED STATES PATENT OFFICE.

EDMUND MORRIS, OF BURLINGTON, NEW JERSEY.

SLATE-FRAME.

Specification of Letters Patent No. 11,134, dated June 20, 1854.

To all whom it may concern:

Be it known that I, EDMUND MORRIS, of Burlington, in the county of Burlington and State of New Jersey, have invented a new and Improved Method for Making Frames for Ciphering-Slates; and I do hereby declare that the following is a full and exact description thereof, reference being had to the accompanying drawings and 10 to the letters of reference marked thereon.

The nature of my invention consists in making the frame with one joint only, instead of four, as in the common old-fashioned frames, by inclosing the slate between 15 two parallel surfaces of wood or other suitable material, and cementing the whole firmly together by means of a water proof glue, aided by nails, if found desirable.

To enable others skilled in the art to 20 make and use my invention, I will proceed to describe its construction and operation.

I first take two pieces of board, of suitable size, a quarter inch thick, and by any tool adapted to the object, cut out two oblong squares of equal size, with the corners 25 rounded, as seen at A A. These are hollow long squares of equal size, with the centers of the board taken out, having a rim of a width proper for the size of the slate about to be framed. 30 By means of any convenient tool, I then cut a rabbet B on the face of each rim, next to its inner edge, the depth of which rabbet is equal to one half the thickness of the slate, so that when the two rims are placed 35 in contact, the slate will fill up the whole rabbet, and be held secure and firm. One of these rims being laid on a table, with the rabbet face upward, the whole upper surface is covered with marine glue or other

40 suitable cement, and the slate dropped into the rabbet. The other rim, also coated with glue on its rabbeted face, is then laid down on the first, after which, the frame thus completed, is taken and compressed by any

convenient process, so as to cause the whole 45 to adhere firmly together. It is then smoothed off, and the completed frame, as ready for market, is shown by Figure C, having but a single joint, which is slightly visible on the outer edge of the frame. 50

The grain of the wood of one half the frame runs across the grain of the other half. This arrangement of the grain, combined with the great surface on which the cement is made to act, braces the frame so 55 thoroughly as to make it much stronger than the old-fashioned frame, whose whole strength is dependent on a slight wooden peg at each corner, continually liable to break, or to drop out by shrinking of the 60 wood. There is, moreover, no disagreeable rattling of the slate in its frame, as it is tightly cemented to the wood work, while this frame can be made at a less price, as there is no loss of lumber, the center piece 65 from each rim being cut up to form a frame for the next smaller size. And as nearly all sawing up of the stuff is dispensed with a cheaper class of labor can be employed in manufacturing them. The substitution of 70 the round corners for the sharp angular ones now in use, possesses the merit of saving the desk from being bruised and otherwise indented, as is now done by the striking of the aforesaid sharp corners upon it. 75

What I claim as my invention and desire to secure by Letters Patent, is—

Constructing a slate frame of corresponding halves, of such a shape that a single joint combines them with each other at 80 the same time that it firmly secures the slate between them, substantially as herein set forth.

EDMUND MORRIS.
